DESIGN FOR A LIGHTING FIXTURE

Clyde D. McCann, Des Moines, Iowa

Application March 27, 1948, Serial No. 145,401

Term of patent 14 years

(Cl. D48—4)

To all whom it may concern:

Be it known that I, Clyde D. McCann, a citizen of the United States, residing at Des Moines, in the county of Polk and State of Iowa, have invented a new, original, and ornamental Design for Lighting Fixture, of which the following is a specification, reference being had to the accompanying drawing, forming a part thereof.

Fig. 1 is a front view, Fig. 2 is a right side view, Fig. 3 is a left side view, Fig. 4 is a top view, and Fig. 5 is a bottom view of a lighting fixture, showing my new design.

I claim:

The ornamental design for a lighting fixture, substantially as shown.

CLYDE D. McCANN.
